UNITED STATES PATENT OFFICE

161,430

AUTOMOBILE

Howard A. Darrin, Los Angeles, Calif.

Application February 28, 1948, Serial No. 144,830

Term of patent 7 years

(Cl. D14—3)

To all whom it may concern:

Be it known that I, Howard A. Darrin, a citizen of the United States and resident of the city of Los Angeles, county of Los Angeles, State of California, have invented a new, original, and ornamental Design for Automobile, of which the following is a specification, reference being had to the accompanying drawings, forming a part hereof, in which:

Fig. 1 is a top plan view of the automobile embodying my new design;

Fig. 2 is a side view;

Fig. 3 is a rear end view; and

Fig. 4 is a front end view thereof.

I claim:

The ornamental design for an automobile, substantially as shown.

HOWARD A. DARRIN.
